UNITED STATES PATENT OFFICE.

ARTHUR TREVOR DAWSON AND GEORGE THOMAS BUCKHAM, OF WEST-MINSTER, LONDON, ENGLAND, ASSIGNEES TO VICKERS SONS & MAXIM, LIMITED, OF LONDON, ENGLAND.

GUN-MOUNTING.

SPECIFICATION forming part of Letters Patent No. 718,050, dated January 6, 1903.

Original application filed December 9, 1901, Serial No. 85,296. Divided and this application filed October 16, 1902. Serial No. 127,591. (No model.)

To all whom it may concern:

Be it known that we, ARTHUR TREVOR DAWSON, lieutenant of Royal Navy, and GEORGE THOMAS BUCKHAM, engineer, both residing at 5 32 Victoria street, Westminster, in the county of London, England, subjects of the King of Great Britain, have invented certain new and useful Improvements in and Relating to Gun-Mountings, of which the following is a specification.

This invention relates to quick-firing and other gun mountings that are provided with a hydraulic buffer for absorbing the energy of recoil and a recuperator for running the gun forward to firing position after recoil. The chief object of our invention is to provide means for controlling the velocity with which the gun runs forward after recoil, said invention being applicable to that form of recoil-buffer in which the cylinder has a hollow piston-rod and a retarding-ram extending inwardly from one end of the cylinder into the said hollow piston-rod. The piston is partly withdrawn from the ram during recoil, thereby leaving in the piston-rod a space which becomes filled with liquid that must be displaced by the ram while the gun is being run forward after recoil, provision being made for the displaced liquid to be forced through a restricted passage, thus controlling the velocity with which the gun is returned to its firing position. In the specification of another application for patent, Serial No. 85,296, of 1901, we have described for accomplishing this purpose means whereby the liquid in the hollow piston-rod can only escape back to the recoil-cylinder through an opening or passage which gradually diminishes in area during the forward movement of the piston as the gun regains its firing position. According to our present invention we for this purpose provide the inner end of the aforesaid ram with a valve arrangement which operates with taper passages on the hollow piston-rod, as hereinafter explained.

In the accompanying drawings, Figure 1 is a longitudinal section of a recoil-cylinder provided with our improvements. Figs. 2 and

3 are transverse sections thereof, taken, respectively, on the lines 1 1 and 2 2.

A is the recoil-cylinder; B, the hollow piston-rod; B', its piston; C, the ram, which projects from one end of the cylinder and enters the hollow piston-rod.

A' is the key within the cylinder A, and 55 B² the aperture in said piston, that acts in conjunction with said key for increasing the resistance to the recoil as said piston travels in the cylinder during the recoil movement of the gun.

C is the lug or bracket on the gun, to which the piston-rod is secured.

b b are inclined passages formed through the hollow piston-rod and serving to connect the annular space existing between the ram 65 C and the hollow piston-rod with the space a in the cylinder A behind the piston.

Along the interior surface of the hollow piston-rod are formed one or more longitudinal taper grooves b⁶, which open at their ends 70 of greater area into the passage or passages b, through which communication is established between the space a of the recoil-cylinder and the interior of the hollow piston-rod. The said taper grooves extend rearwardly and gradually diminish in area until they merge into the cylindrical inner surface of the hollow piston-rod at about the point b⁷.

b⁸ is a non-return valve at the inner or rear end c² of the ram, at which end said ram is 80 furnished with a cap c³, whose outer diameter fits the interior of the hollow piston-rod B and is formed with a longitudinal groove or passage c⁴. The end c² of the ram is also formed with a central hole c⁵, which extends 85 forwardly and diverges at c⁶ to the circumference at a point in advance of the forward end of said cap c³. At the mouth of the said hole c⁵, within a space c⁷ provided for its reception, is located the non-return valve b⁸. 90 The end of the said cap c³ is perforated at c⁸ c⁹ to permit of liquid reaching the said space c⁷ from the interior of the hollow piston-rod. During recoil of the gun the pressure in the space a of the cylinder A forces the liquid 95 through the passage b in the piston-rod B into

the annular space around the ram C, thence through the holes c^6 c^5 in said ram, past the valve b^5 , and through the perforations c^6 in the cap c^8 , whereby said liquid reaches the space within the hollow piston-rod and keeps it filled with liquid as the rod is withdrawn from the ram C. On the completion of the recoil and in the return movement of the gun the aforesaid valve b^5 , under the pressure of the liquid within the hollow piston-rod, closes the passage c^5 . Consequently the only way of escape left for the liquid from said hollow piston-rod is by the small groove c^4 in the cap c^8 and the taper grooves b^6 in the piston-rod, leading to the passages b . As these grooves b^6 gradually diminish in area, it follows that during the return movement of the piston and its rod the gun will be very gradually brought to rest as it terminates its forward movement.

What we claim, and desire to secure by Letters Patent of the United States, is—
In recoil apparatus for guns, the combination

of the ram and the hollow piston-rod having passages therein capable of communicating with the interior and exterior of the said hollow piston-rod, of a non-return valve located near the inner or rearward end of the ram and of a perforated cap having a chamber inclosing said non-return valve and communicating with a passage in the ram leading to opposite ends of said perforated cap; said cap being of a diameter to fit the hollow piston-rod and formed in its periphery with a longitudinal passage adapted to coöperate with a tapered passage in the interior of the hollow piston-rod, substantially as and for the purpose specified.

In testimony whereof we have hereunto set our hands, in presence of two subscribing witnesses, this 6th day of October, 1902.

ARTHUR TREVOR DAWSON.
GEORGE THOMAS BUCKHAM.
